PICKER STICK CONNECTION

Joseph Vanore, Haledon, N. J.

Application July 8, 1947, Serial No. 759,541

6 Claims. (Cl. 139—151)

1

My invention relates to looms and more particularly to means whereby the picker stick may be adjusted for regulating the power and stroke thereof for driving the shuttle.

While I am aware that the prior art discloses various devices and adjustments for regulating the power and stroke of the picker stick, for instance, United States Patents Nos. 434,988; 1,392,126; 1,481,195 and 1,579,078, these devices or mechanisms are usually of a somewhat complicated construction and necessitate substantial modification of standard loom parts in order to apply or attach them to looms already in use. Furthermore, when incorporated as part of the initial or standard construction of looms, they materially increase the production costs thereof.

My invention overcomes the foregoing difficulties and disadvantages, it being one of the objects thereof to provide means whereby the picker stick may be readily adjustable relative to the operating crank arm and which means is simple in construction, durable in use, efficient in operation, economical in manufacture, and lends itself to ready application of looms already in use without substantially modifying the latter.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a perspective view of my invention as attached to the associated operating parts of a loom.

Figure 2 is a side elevation thereof.

Figure 3 is an end elevation.

Figure 4 is a sectional view taken on the line 4—4 of Figure 1.

Figure 5 is a perspective view illustrating a modification in the arrangement of certain components.

Figure 6 is a side elevation of the modification.

Figure 7 is an end elevation of the modified arrangement disclosed in Figures 5 and 6.

Figure 8 is a sectional view taken on the line 8—8 of Figure 5.

In practicing my invention, as illustrated in Figures 1 to 4 of the drawings, I employ a picker stick 10 of ordinary construction having its upper end equipped with the usual shuttle engaging pad or member 11 and its lower end pivoted, as at 12, to a rocker-iron 13 carried by the loom, the latter being equipped with the usual crank arm 14 for operating the stick 10.

The crank arm 14 is provided with an upper

2

outwardly curved end section 15 attached to one end of an operating bar or arm 16 formed with an opening 17. The end section 15 is formed with an opening 18 through which extends a bolt 19 provided with a nut 20. The bolt 19 also extends through the opening 17 in the operating bar or arm 16 and constitutes a pivot permitting relative movement of the arm 14 and bar 16. The opposite end of the bar 16 is formed with a plurality of openings 21 and is embraced by coincident end sections of a pair of elongated plates or members 22, one of said end sections having fixed thereto a pivot pin 23 which extends through one of the openings 21 and into a similar opening formed in the coincident end section of the opposite plate whereby to form a pivotable connection between the bar 16 and the plates 22.

The opposite end sections of the plates 22 embrace the side faces of the picker stick 10 and are formed with elongated registering slots 24 through which extends a clamping bolt 25 provided with a nut 26. The bolt 25 extends through an opening 27 formed in the stick 10 superjacent the rocker-iron 13 and, when the nut 26 is tightened, serves to clamp the plates 22 to the stick 10 and thus establishes a fixed connection between the plates and stick.

Obviously, operating of the crank arm 14 will impart reciprocating motion to the picker stick 10 for projecting or driving the shuttle across the lay of the loom in the usual manner, it being understood that the plates 22 pivot relative to the bar 16 during this operation. Should it be desired to regulate the stroke and power of the stick for driving the shuttle, the nut 26 is loosened and the plates 22 adjusted relative to the picker stick 10 and bar 16 to effect the desired length of the stroke, as illustrated in dotted and full lines in Figure 2 of the drawings, whereupon the nut 26 is again tightened to clamp the plates in fixed relation to the stick. In the event that a relatively large adjustment is required to obtain the desired stroke of the picker stick, the pivot 23 may be transposed from one of the openings 21 to another.

As illustrated in Figures 6 to 8 of the drawings, the plates 22 may be endwisely reversed with the pivot pin 23 extending through the opening 27 of the stick to form pivotable connection therewith while the bolt 19 extends through one of the openings 21 of the bar 16 to establish a fixed connection between the bar and the plates during operation of the stick. Obviously, by adjusting the plates relative to the bar and transposing the bolt 19 from one to another of the openings 21, the stroke of the picker stick may be varied as desired.

Without further elaboration, the foregoing will so fully explain the invention that others may, by applying current knowledge, readily adapt the

same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In combination with a pivoted picker stick member formed with an opening adjacent its pivot and a crank arm for operating said stick member; a bar member having one end pivotally connected to said crank arm and its opposite end formed with a plurality of openings, a pair of plates having end sections embracing said opposite end of said bar member and said stick member, a pivot pin extending through coincident end sections of said plates and fixed to one of the latter and with said pin extending through one of said openings in one of said members to form a pivotable connection therewith, the other end sections of said plates being formed with registering elongated slots, and a clamping bolt extending through said slots and an opening in said other member for clamping said plates to said last mentioned member.

2. In combination with a pivoted picker stick member formed with an opening adjacent its pivot and a crank arm for operating said stick member; a bar member having one end pivotally connected to said crank arm and its opposite end formed with a plurality of openings, a pair of plates having end sections embracing said opposite end of said bar member and said stick member, a pivot pin extending through coincident end sections of said plates and fixed to one of the latter and with said pin extending through one of said openings in said bar member to form a pivotable connection therewith, the other end sections of said plates being formed with registering elongated slots, and a clamping bolt extending through said slots and the opening in said stick member for clamping said plates to said stick member.

3. In combination with a pivoted picker stick member formed with an opening adjacent its pivot and a crank arm for operating said stick member; a bar member having one end pivotally connected to said crank arm and its opposite end formed with a plurality of openings, a pair of plates having end sections embracing said opposite end of said bar member and said stick member, a pivot pin extending through coincident end sections of said plates and fixed to one of the latter and with said pin extending through said opening in said stick member to form a pivotable connection therewith, the other end sections of said plates being formed with registering elongated slots, and a clamping bolt extending through said slots and one of said openings in said bar member for clamping said plates to said last mentioned member.

4. A picker stick actuating device for opera-

tively connecting the crank arm of a loom to a pivoted picker stick member having an opening adjacent its pivot; comprising a bar member adapted to have one end pivotally connected to the crank arm and its opposite end being formed with a plurality of openings, a pair of plates having end sections embracing said opposite end of said bar member and opposite end sections adapted to embrace said stick member; a pivot pin extending through coincident end sections of said plates and fixed to one of the latter to dispose said pin through one of said openings in one of said members to form a pivotable connection therewith, the other end sections of said plates being formed with registering elongated slots, and a clamping bolt disposed through said slots for clamping said plates to said other member when said bolt extends through an opening in said last mentioned member.

20 5. A picker stick actuating device for operatively connecting the crank arm of a loom to a pivoted picker stick having an opening adjacent its pivot; comprising a bar adapted to have one end pivotally connected to the crank arm and its opposite end being formed with a plurality of openings, a pair of plates having coincident end sections embracing said opposite end of said bar and opposite end sections adapted to embrace said stick; a pivot pin extending through coincident end sections of said plates and fixed to one of the latter and with said pin extending through one of said openings in said bar to form a pivotable connection therewith, the other end sections of said plates being formed with registering elongated slots, and a clamping bolt disposed through said slots for clamping said plates to said stick when said bolt extends through the opening in said stick.

6. A picker stick actuating device for operatively connecting the crank arm of a loom to a pivoted picker stick having an opening adjacent its pivot; comprising a bar adapted to have one end pivotally connected to the crank arm and its opposite end being formed with a plurality of openings, a pair of plates having coincident end sections embracing said opposite end of said bar and opposite end sections adapted to embrace said stick; a pivot pin extending through coincident end sections of said plates and fixed to one of the latter to dispose said pin through said opening in said stick to form a pivotable connection therewith, the other end sections of said plates being formed with registering elongated slots, and a clamping bolt disposed through said slots for clamping said plates to said bar when said bolt extends through one of said openings in said bar.
